No Printed Specification Available

3739X

J. BAZIN, JR.

Loom Tension.

No.

Patented Aug. 8, 1823.

32325

References.

See John Burzin Jun. Temples, for Cloth Looms.

Patented 1811.

Fig. 1. Represents the temples on the cloth, as stricken out.

Fig. 2. The same in perspective, and open.

Fig. 3. The centre frame, marked D. in figures 1 & 2.

Fig. 4. Is the left hand slider, or temple end; drawn with the under side to show the plate e.

Fig. 5. Is the right hand slider; the jointed piece fig. 6 being left out. Both sliders are marked C. in figures 1 & 2.

Fig. 6. Represents parts of the loom, to shew how the temples are worked in and out in the loom, to work the temples. A. is the main frame of the loom, to shut the temples. B. the cross frame of the loom, to work the temples. C. is the block D. to work the temples, and pull them together whenever they open. E. weight, to counterpoise the lever E.